UNITED STATES PATENT OFFICE

RICHARD W. LEIBERT, OF PITTSBURGH, PENNSYLVANIA

DESIGN FOR A SIGN PLATE FOR AN AUTOMOTIVE SIGNAL

Application filed June 20, 1931. Serial No. 40,283. Term of patent 3½ years.

To all whom it may concern:

Be it known that I, RICHARD W. LEIBERT, a citizen of the United States, residing at Pittsburgh, county of Allegheny, and State of Pennsylvania, have invented a new, original, and ornamental Design for a Sign Plate for an Automotive Signal, of which the following is a specification, reference being had to the accompanying drawing, forming part thereof.

The figure is an elevational view of a sign plate for an automotive signal, showing my new design.

The design has no appreciable thickness.

I claim:

The ornamental design for a sign plate for an automotive signal, as shown and described.

RICHARD W. LEIBERT.
